UNITED STATES PATENT OFFICE

JOHN M. READEY, OF ST. LOUIS, MISSOURI, ASSIGNOR TO JOHN M. READEY, INC., OF ST. LOUIS, MISSOURI, A CORPORATION OF DELAWARE

PIPE CUT-OFF MACHINE

Application filed July 21, 1930. Serial No. 469,378.

This invention relates to new and useful improvements in pipe cut-off machines, the objects of the invention being the provision of a cut-off machine having a revoluble cutter arranged in stationary bearing and having a pipe support operable by fluid pressure to raise the pipe supported thereon and bring it in engagement with the cutter.

Other objects of the invention are to operate the cam shaft, used to raise and lower the pipe support, by means of an operating mechanism actuated by fluid pressure whereby the movement of the support is controlled by a suitable valve which regulates the admission of the fluid to the operating cylinder.

Further objects of the invention are to provide a roller cage having a plurality of rollers of varying sizes arranged in pairs to support pipes of different sizes, said cage being adjustable to bring various rollers in supporting positions so that said pipe cut-off machine is readily adaptable for operation upon various sizes of pipes without requiring the replacement of the pipe supports or parts thereof.

Additional objects of the invention are to improve the construction of pipe cut-off machines so as to render it more efficient in operation and enable the production of short lengths of pipes and nipple blanks and the like on a large scale and in an inexpensive manner.

With these and other objects in view, my invention consists in certain novel features of construction and arrangement of parts, hereinafter more fully described and claimed, and illustrated in the accompanying drawings, in which—

Figure 1 is a side elevational view of my improved pipe cut-off machine.

Figure 2 is a front elevation thereof.

Figure 3 is an enlarged vertical cross section taken on line 3—3 of Figure 1.

Figure 4 is an enlarged vertical cross section taken on line 4—4 of Figure 1.

Figure 5 is an enlarged detail view, partly in cross section, of the height regulating means.

Figure 6 is a cross section of the valve uti-

lized to control the admission of fluid to the cylinder.

Heretofore in the operation of machines of this type, the pipe support was raised by means of a pedal which actuated a suitable cam shaft and rocked a cam carried thereby. This cam, when actuated, raised, through an adjusting screw, the support carrying the pipe so that the latter was brought into engagement with the cutter. This arrangement has not been satisfactory as the production was not fast enough to enable the manufacture of the product on a satisfactory commercial basis. This was partly due to the fact that the support and the pipe carried thereby were raised by the force applied by the operator who also had to supervise the operation of the machine.

In my present invention, I utilize compressed air to raise the pipe support and the operator's energy is reserved for operating the valve controlling the admission of compressed air to the operating cylinder so that he can devote more attention to the operation of the machine and the production rate can be considerably increased.

Referring by numerals to the accompanying drawings, 10 indicates a support or frame provided with a base 11, and carrying at its upper end a rotary cutter or disk 12. This disk is mounted on a horizontally disposed revoluble shaft 13 which is mounted in bearing 14 of said frame 10. Shaft 13 is actuated by any suitable mechanism, such as gearing 15. The driving shaft 16 can be driven either by an electric motor or, as shown, by a pulley 17.

A pipe support 18 is disposed below cutter 12 and is operable in a vertical plane to position the pipe relatively to said cutter. This support comprises a cage 19 pivotally mounted on a horizontally disposed shaft 20. Two or more pairs of rollers 21 and 22 are provided on said cage. These rollers are freely mounted in said cage and said parts are of different sizes so that the large rollers 21 can be used to support the smaller sized pipes and the small rollers 22 can be used to support large sized pipes.

Shaft 20 is mounted in a suitable bearing 23 which is carried by the upper end of a verti-

cally disposed bar 24. This bar is slidably mounted in a bearing 25 projecting outwardly from frame 10. The lower end of bar 24 is provided with a bifurcated member 26 in which is arranged a horizontally disposed stud shaft 27. A roller 28 is freely journaled on said shaft and rests in one of the seats formed in the upper end of an adjusting member 29. There are two or more seats 29^a and 29^b arranged at varying radial distances from the axis of shaft 27. Seat 29^a is further away from shaft 27 and when roller 28 occupies this seat the roller cage 19 occupies raised position. When member 29 is moved to cause roller 28 to engage seat 29^b which is deeper and therefore closer to the axis of shaft 27, the cage 19 occupies depressed position. Thus by adjusting member 29 the distance between the rollers of the cage and the cutter can be varied in addition to the adjustment of the cage itself. A handle 29^c is formed on member 29 to facilitate manual operation thereof.

Member 29 is mounted by means of a horizontally disposed shaft 30 in the upper end of a vertically disposed plunger 31. A bearing 32 projecting outwardly from bar 10 provides a guide for said plunger 31. The lower end of this plunger carries a roller 33 which rides upon a cam 34. This cam is fixed to a horizontally disposed shaft 35 and is so shaped that when said shaft is rocked in the direction indicated by the arrow, the high point 35^a of said cam is brought into engagement with roller 33, thereby raising plunger 31 and bar 24 so that the pipe supported by the appropriate pair of rollers 21, or 22, is brought into engagement with cutter 12.

Shaft 35 is actuated in one direction by a connecting rod 36, one end of which is connected to the upper end of arm 37, whose lower end is fixed to shaft 35. Connecting rod 36 is connected at its opposite end to a piston rod 38 which carries a piston 39 operating in a cylinder 40.

This piston is actuated by compressed air supplied to said cylinder by a connection 41 and is controlled by a valve 42 which is interposed in said connection. This valve is operated by means of a pedal 43 which has one end connected by a rod 44 to an actuating arm 45 of said valve. This valve is provided with an exhaust port 42^a which, when the pedal is released and the valve brought to normal position, connects the interior of the cylinder with the atmosphere and allows the air to be discharged from the cylinder. When the air pressure is removed from the cylinder, piston 39 and cam 34 are restored to their normal or inactive positions by means of a coiled spring 46 which is stationarily anchored at one end and is connected at the other end to an arm 47 fixed at its other end to shaft 35. No restoring means are needed to bring the pipe support and bar 28 to nor-

mal positions as these are restored of their own weight as soon as cam 33 is brought to home positions.

Preferably a coiled spring 48 is connected at one end to an extension 27^a of pin or shaft 27 and at the other end to an extension 30^a of pin or shaft 30. The tension of said spring serves to hold roller 28 yieldingly to its seat in plate 29.

In order to lock roller cage 19 in adjusted position, one side thereof is provided with two spaced apertures 49 and member 23 is formed with an extension 23^a having an aperture receiving a pin 50. When cage 19 is properly adjusted, one of its apertures 49 registers with aperture in extension 23^a so that pin 50 can engage said aligned apertures and lock the cage in position.

To lock plate 29 in adjusted position, a pin 51 is used. This can is detachably seated in an aperture formed in extension 52 of member 31 and is engageable with either one of a pair of spaced apertures 53 formed in plate 29 at the appropriate points. The adjustments can be made quickly and require no experienced mechanic. This not only saves time but dispenses with the services of expensive labor.

When the adjustments are made, the workman has no other duties to perform except to feed the pipe to the cutter disk and operate the pedal 43.

The pedal 43 is used merely to operate valve 42 and the pressure necessary to raise the support 18 and hold the pipe against the cutter disk 12 is furnished by the cylinder 40. The pressure of the fluid used to operate the piston is regulated so that only the required pressure is applied to the piston.

My invention, which is particularly desirable in the manufacture of nipples, is of simple construction and can be attached to existing types of cut-off machines.

While I have shown herein the preferred form of my invention, it is obvious that various changes in the construction and arrangement of parts of my improved cut-off machine can be made and substituted for those herein disclosed without departing from the spirit of my invention.

I claim:

1. A pipe cut-off machine comprising in combination a frame, a pipe cutter disk revolvably mounted thereon, a slidable plunger mounted in said frame below said disk for movement in a vertical plane, a roller cage mounted on the upper end of said plunger and provided with a pair of spaced rollers for supporting the pipe relatively to said cutter, a rock shaft, a cam fixed on said shaft and engaging the lower end of said plunger for raising the same, and fluid pressure operated means for actuating said shaft.

2. In a pipe cut-off machine, the combination of a support frame, a pipe cutter disk

revolubly mounted thereon, a plunger slidably mounted on said frame for movement in a vertical plane, a roller cage mounted on the upper end of said plunger and provided with a plurality of seats for supporting a pipe relatively to said cutter, said cage being pivotally mounted on said plunger and said seats being differentially disposed with respect to the axis of said cage whereby pipes of various sizes can be supported by said cage, each of said seats comprising a plurality of rollers, means for locking said cage in adjusted position on said plunger, a rock shaft journaled in said frame, a cam fixed to said shaft, and a roller riding upon said cam and mounted on said plunger and actuating the latter.

3. In a pipe cut-off machine, the combination of a support frame, a pipe cutter disk operatively mounted on said frame, a pipe support mounted on said frame for movement in a vertical plane relatively to said cutter, said pipe support including a cage carried by the upper end of said support, a roller operatively associated with said support, a horizontally disposed rock shaft journaled on said frame, a cam fixed on said shaft and engaging said roller for raising said pipe support and bringing the pipe carried thereby into engagement with said cutter, a rock arm extending from said shaft, a fluid pressure cylinder, a piston operating therein, connections between said piston and said rock arm for actuating said rock shaft, a valve for controlling the admission of fluid to said cylinder, and a pedal for actuating said valve.

4. In a device of the class described, the combination of a support frame, a pipe cutter disk revolubly mounted in said frame, a pipe support operatively mounted for movement in a vertical plane relatively to said cutter disk, said pipe support including a vertically disposed slidable bar carrying at its upper end a pair of rollers arranged in spaced relation with each other and adapted to receive the pipe to be operated upon, a vertically disposed slidable plunger mounted on said frame below said bar, means carried by the upper end of said plunger for operatively engaging the lower end of said bar, said means being adjustable to regulate the distance below said plunger and said bar, a roller carried by the lower end of said plunger, a rock shaft, a cam fixed on said shaft and engaging said roller for raising and lowering said pipe support, a fluid pressure cylinder, a piston operating therein, means operatively connecting said piston with said rock shaft for actuating the latter by fluid pressure exerted against said piston, a valve in said cylinder for controlling the admission to and the exhaust from said cylinder of a suitable fluid under pressure, and means for actuating said valve.

5. In a machine of the class described, the combination of a support frame, a pipe cutter

disk revolubly mounted on said frame, a vertically disposed bar slidably mounted in said frame, a pipe support member carried by the upper end of said bar and adjustable relatively thereto to accommodate pipes of various diameters, a vertically disposed plunger slidably mounted in said frame below said bar, an adjusting member mounted on the upper end of said plunger and engaging the lower end of said bar, said member being adjustable to regulate the distance between the upper end of said bar and the upper end of said plunger, a roller carried by the lower end of said plunger, a horizontally disposed rock shaft, and a cam fixed to said shaft and engaging said roller, to raise said plunger and said bar and bring the pipe supported by said pipe support into engagement with said cutter.

6. In a machine of the class described, the combination of a support frame, a pipe cutter disk revolubly mounted on said frame, a vertically disposed bar slidably mounted in said frame, a pipe support member carried by the upper end of said bar and adjustable relatively thereto to accommodate pipes of various diameters, a vertically disposed plunger slidably mounted in said frame below said bar, an adjusting member mounted on the upper end of said plunger and engaging the lower end of said bar, said member being adjustable to regulate the distance between the upper end of said bar and the upper end of said plunger, a roller carried by the lower end of said plunger, a horizontally disposed rock shaft, a cam fixed to said shaft and engaging said rollers, and means for operating said rock shaft.

7. In a machine of the class described, the combination of a support frame, a pipe cutter disk operatively mounted on said frame, a vertically disposed bar slidably mounted in said frame, a roller cage mounted on the upper end of said bar, a pair of rollers mounted in said cage and adapted to support a pipe to be operated upon by said cutter, a roller arranged on the lower end of said bar, a vertically disposed plunger slidably mounted on said frame below said bar, an adjusting member carried by the upper end of said plunger and operatively supporting the roller of said bar, said adjusting member being adjustable to regulate the position of said cage relatively to said cutter, a rock shaft journaled in said frame below said plunger, a cam fixed on said shaft and engaging the lower end of said plunger, and a coiled spring for holding said shaft in a position whereby said plunger engages the low point of said cam.

8. In a machine of the class described, a pipe support means comprising a slidably mounted vertically disposed bar, a roller cage pivotally mounted upon the upper end thereof and including a plurality of rollers arranged in pairs, each pair being differential.

ly disposed relatively to the axis of said roller cage for accommodating pipes of various sizes, means for locking said cage in adjusted position relatively to said bar, a roller carried by the lower end of said bar, a vertically disposed slidable plunger arranged below said bar, an adjusting plate pivotally mounted on the upper end of said plunger and provided with a plurality of seats for engaging the roller of said bar, said seats being of various depths so as to vary the distance between said plunger and said roller cage, a roller carried by the lower end of said plunger, a cam engaging said last mentioned roller, and means for actuating said cam to raise or lower said plunger and said bar so as to position the pipe supported by said roller cage relatively to the pipe cutting means.

9. In a machine of the class described, the combination with a revolute pipe cutter disk, of a pipe support means comprising a slidably mounted vertically disposed bar, a roller cage pivotally mounted upon the upper end thereof, a plurality of horizontally disposed rollers journaled in said cage and arranged in pairs, each pair being differentially disposed relatively to the axis of said roller cage for accommodating pipes of various diameters, means for locking said cage in adjusted positions relatively to said bar, and means for operating said bar relatively to said pipe cutter disk.

10. In a machine of the class described, the combination with a revolvably mounted pipe cutter disk, of a pipe support means including a slidable vertically disposed bar, a pipe engaging means carried by the upper end of said bar, a vertically disposed slidable plunger arranged below said bar, an adjusting plate pivotally mounted on the upper end of said plunger and provided with a plurality of seats for engaging the lower end of said bar, said seats being of various depths so as to vary the distance between said plunger and the upper end of said bar, and means for engaging the lower end of said plunger and operating said bar.

In testimony whereof I hereunto affix my signature this 21st day of June, 1930.

JOHN M. READEY.
